UNITED STATES PATENT OFFICE.

ALBERT ASLESON, OF REDWOOD FALLS, MINNESOTA.

CATARACT ABSORBER.

Application filed August 19, 1927. Serial No. 214,124.

My invention relates to cataract absorbers and has for its object to provide an enclosed shield adapted to be placed over the eyes of the patient and provided with an electric heating element whereby the heat generated in the eye shield will be utilized in the treatment of the eyes of the patient.

A further object is to provide a switch box remotely arranged with respect to the shield and adapted to selectively control the heating element within the shield for the treatment of either eye of the patient.

Another object of the invention is to interpose a rheostat in the electric circuit and locate the same in the switch box whereby the intensity of the heat developed in the shield may be regulated.

Other objects and advantages reside in the special construction and combination of the various elements constituting the invention, reference being had to the accompanying drawings forming a part hereof, wherein:

Figure 1 is a perspective view showing my invention in operative position.

Figure 2 is a bottom plan view of the shield.

Figure 3 is a vertical sectional view therethrough.

Figure 4 is a similar view through the switchbox.

Figure 5 is a transverse sectional view taken along a line 5—5 of Figure 4.

Figure 6 is a diagrammatic view showing the electric circuit, and,

Figure 7 is a vertical sectional view showing a modified form of heating element.

Referring to the drawings in detail, I have shown my invention comprising an eye shield indicated at 5 of a generally rectangular construction and having its bottom portion shaped to snugly fit over the eyes of a patient and having a lower partition 6 set tightly inwardly from the bottom edge of the shield and in substantially parallel relation therewith; said partition forming a compartment therebetween, and with the upper edge of the shield, within which is mounted a pair of heating elements 7 in the nature of electric coils.

Electric wires 10 extend from the heating element to a switch box indicated at 11 which may be mounted in any suitable position remote from the shield 5. The compartment within the shield is lined with a suitable heat insulation material indicated at 12 arranged along the top and sides of the shield so that the heat generated within the compartment

by means of the heating element will be directed against the partition 6 which, when arranged in operative position, is disposed slightly above the eyes of the patient. The partition 6 is preferably constructed of a suitable heat absorbing light weight metal, such as aluminum, or the like, whereby the heat generated within the compartment will be quickly transmitted therethrough and at the same time protects the eyes of the patient from the direct force of the heat.

The partition 6 is formed into sections secured at their sides to the sides of the shield and their inner adjacent edges 8 and above the partition in spaced relation therefrom, thereby forming pockets for retaining the heating element therein. The adjacent edges of the partition are spaced apart with a nose guard 9 interposed therebetween.

The switch box 11 is preferably constructed of insulation material having a cover plate 11' removably fitted thereon into which extends a pair of switch handles 14, each handle operating a switch 14' arranged within the switch box and connected by the wire 10 from the control of one of the heating elements 7 within the shield. A rheostat 15 is also mounted within the switch box having an operating handle 16 extending therefrom outwardly of the box, whereby to regulate the intensity of the heat transmitted to the heating element. A cable 17 connects the rheostat with the outside by means of a plug 18.

A pad of insulation material 13' may also be placed about the heating element to prevent the heat from penetrating into the compartment.

The heating element may comprise any suitable form and in Figure 7 I have indicated a modified form thereof constituting a pair of electric light bulbs 19, arranged within the shield and adapted by means of the heat generated thereby when lighted, to obtain the desired result.

The bulbs may be carried in the socket 19 of the usual type secured in the sides of the shield and having the electric wires 10 connected therewith. In this form of the invention, the partition 20 is in a single piece extending entirely across the underside of the shield and supported at its center by a bolt 21.

In the treatment of the eyes of a patient, a cloth pad indicated at 22 may first be placed upon the eyes in order to protect the patient

from injury by the edges of the shield and by placing the shield in proper position, it is apparent that the heat of a suitable intensity may be directed against either eye of the patient by means of the proper manipulation of the rheostat and switches within the switch box.

It is obvious that the invention is susceptible of various changes and modifications without departing from the spirit or scope of the invention as hereinafter claimed or sacrificing any of its advantages, and I accordingly claim all such forms of the device to which I am entitled.

15 I claim:—

In a cataract absorber, an eyeshield having its lower edge shaped to conform with the

contour of the eyes of a person, a partition removably secured within the shield adjacent the lower edge thereof, a pair of electric heating coils mounted within the shield, a heat insulating lining for the top and side portions of the shield, a switchbox remote from the shield, a pair of switch elements operatively arranged within the box and connected respectively to said heating coils whereby to selectively control the same and an electric rheostat mounted within the switchbox having an operating handle extending therefrom, said rheostat being interposed between each of said switch elements and said heating coils.

20 In testimony whereof I affix my signature.

25 ALBERT ASLESON.
